UNITED STATES PATENT OFFICE.

ELLISON T. HARKRADER, OF ST. LOUIS, MISSOURI.

DESIGN FOR A BUTTON.

SPECIFICATION forming part of Design No. 35,890, dated May 6, 1902.

Application filed April 1, 1902. Serial No. 100,985. Term of patent 3½ years.

To all whom it may concern:

Be it known that I, ELLISON T. HARKRADER, of the city of St. Louis, State of Missouri, have invented and produced a new and original Design for a Button, of which the following is a full, clear, and exact description, reference being had to the accompanying drawings, forming a part hereof.

Figure 1 is a front elevation of a button embodying my new design. Fig. 2 is a top plan view.

As shown, the leading or essential feature of my new design for a button comprises the central stem 3, having the three points at its upper end, as shown, and a conventional diamond at its lower end, the crescent 4 uniting with the upper part of the stem 3 to form the

letter "P," the script L⁵ joined to the lower part and upon the left-hand side of the stem 3, and the script E⁶ joined to the lower part 20 of the stem 3 and upon the right-hand side thereof, all of the peculiar form and configuration shown and comprising the letters "L P E."

The fastener 7 projects backwardly from the center of the button. 25

I claim—

The design for a button, substantially as herein shown and described.

In testimony whereof I affix my signature in presence of two witnesses.

ELLISON T. HARKRADER.

Witnesses:

ALFRED A. EICKS,
JOHN C. HIGDON.
